UNITED STATES PATENT OFFICE.

GEORGE J. PIKE, OF GRAND RAPIDS, MICHIGAN, ASSIGNOR TO STAR FURNITURE COMPANY, OF JAMESTOWN, NEW YORK, A CORPORATION OF NEW YORK.

DESIGN FOR A BEDSTEAD.

Application filed May 25, 1928. Serial No. 26,856. Term of patent 3½ years

To all whom it may concern:

Be it known that I, GEORGE J. PIKE, a citizen of the United States, residing at Grand Rapids, in the county of Kent and State of Michigan, have invented and produced a new and original Design for a Bedstead, of which the following is a specification, reference being had to the accompanying drawing, forming part thereof, and in which the figure is a front perspective view of the bedstead, showing my new design.

I claim:

The ornamental design for a bedstead as shown.

GEORGE J. PIKE.
